US00D874757S

(12) **United States Design Patent** (10) Patent No.: **US D874,757 S**
Chei (45) Date of Patent: ** Feb. 4, 2020

(54) **HANDHELD VACUUM COMPONENT**(71) Applicant: **SHARKNINJA OPERATING LLC**,
Newton, MA (US)(72) Inventor: **Junghwan Chei**, Chestnut Hill, MA
(US)(73) Assignee: **SharkNinja Operating LLC**,
Needham, MA (US)(**) Term: **15 Years**(21) Appl. No.: **29/611,764**(22) Filed: **Jul. 25, 2017**(51) LOC (12) Cl. **15-05**

(52) U.S. Cl.

USPC ..... **D32/18**(58) **Field of Classification Search**

Primary Examiner — Ruth McInroy

(74) Attorney, Agent, or Firm — Grossman Tucker
Perreault & Pfleger, PLLC(57) **CLAIM**

The ornamental design of a handheld vacuum component, as shown and described.

DESCRIPTION

FIG. 1 is a front and right-side perspective view of a handheld vacuum component showing my new design;
 FIG. 2 is a front and left-side perspective view thereof;
 FIG. 3 is a bottom and right-side perspective view thereof;
 FIG. 4 is a bottom and left-side perspective view thereof;
 and,

FIG. 5 is a rear view thereof.

The details shown in broken lines form no part of the claimed design.
